CONE DISK TYPE CENTRIFUGAL
SEPARATOR BOWL

Fernand Jean Joseph Julien Henrard, Remicourt,
Belgium, assignor to Ecreteuses Melotte, So-
ciete Anonyme, Remicourt, Belgium, a Belgian
company

Application September 25, 1946, Serial No. 699,212
In Belgium October 5, 1945

2 Claims. (Cl. 233—46)

1

My present invention relates to a centrifugal clarification or separation bowl in which the sediment and purified liquid are evacuated in continuous process.

Although the centrifugal clarification of certain liquids containing solid or semi-solid particles is possible with the known means, the same thing does not apply to the continuous evacuation of these solid particles separated from the liquid by the centrifugal action.

Following their separation with the aid of the known means such as for example a stack of conical plates, these solid particles find their way towards the periphery of the centrifugal bowl where they encounter an obstacle to their natural displacement and on which they accumulate.

This solid or semi-solid sediment cannot therefore reach the evacuation orifices generally located towards the centre of the bowl and by impinging against the inner wall of the bowl they accumulate in a mass which gradually reaches the separating elements, that is to say the conical plates, thus rendering the latter ineffective. The inner elements of the bowl thus become choked, the separation no longer takes place and the clarifier has to be stopped and the bowl cleaned out.

The frequency of this cleaning operation increases with the quantity of solid particles contained in the liquid to be clarified which constitute a serious drawback because the efficiency of the clarifier is thus considerably reduced.

My present invention has for its object to remedy this drawback and is characterised essentially by the fact that the internal wall of the bowl is formed of angular faces which converge towards the evacuation orifices in the external wall of the bowl and by the fact that the inside of the bowl is so designed that it exhibits no surface which through lack of inclination is likely to hold back the heavy particles during their displacement towards the periphery of the bowl.

In carrying the invention into practical effect the angular surfaces combine with the shape of the bowl which consists of an upper and lower cone contacting at their bases to form funnels which continuously drain off the separated substances towards the evacuation orifices provided in the outer wall of the bowl.

The evacuation orifices are formed by very short grooves arranged tangentially in one of the two contact surfaces of the two halves of the bowl or in both the said contact surfaces.

Preferably the two half-bowls are centred one

2

on the other by means of a flange provided on the upper half-bowl and which engages on the upper peripheral rim of the lower half-bowl, the said flange being recessed opposite to the outlet orifices, the two half-bowls being juxtaposed without the insertion of a joint of rubber or other analogous material and in such a manner that the only parts which do not form a tight joint are those corresponding to the evacuation orifices.

10 The accompanying drawings illustrate how the invention can be carried into practical effect.

Fig. 1 shows, in its lefthand half a sectional view of the bowl and in its righthand half an elevation showing the outside of the bowl.

15 Fig. 2 is a view from above, the lefthand half being a section and the righthand half an external view.

Fig. 3 is a view showing a detail in vertical section of the method of assembling the upper half-bowl and the lower half-bowl.

20 Figs. 4 and 5 are detailed views of a plate forming part of the stack, the said plate being of course illustrated purely by way of example.

Fig. 6 is a sectional view of a modified embodiment of a bowl.

25 Fig. 7 is a section of a jewel-holder which may advantageously be utilised as a device for evacuating the muddy liquid.

In the accompanying drawings, 1 is the tube 30 through which the liquid to be treated is fed in (following the arrow F) to the distribution chamber 2 forming an integral part of the tube 1; this chamber is closed at the top by contact with the upper half of the bowl 3 which is fitted in the usual manner with a suspension ring 4. Inside the distribution chamber 2 are provided directing vanes 5 intended to impart to the liquid the same angular rotary motion as that of the bowl.

35 Superimposed around the tube 1 is a larger or smaller number of conical plates 6 (for example 50) forming in known manner a stack of plates.

In the embodiment illustrated on Figure 1, these conical plates are each perforated with three holes 7 (Figs. 4 and 5) of circular shape 45 which by superposing the plates form delivery conduits 8 (Fig. 1) for the liquid in the space enclosed between the plates. The base of each conical plate is provided with a guide slot 9 (Fig. 5) which permits of accurately juxtaposing the plates for the purpose of forming the conduits 8.

50 The liquid subjected to the centrifugal force in the chamber 2 is guided into the conduits 8 by short ends of tube 10.

The plates 6 are centred by stacking them around the tube 1 which in turn is guided and

centred by its base in the lower half 11 of the bowl and at the top by a ring 12 which is secured to the vanes 5 and fits into the cylindrical part 13 integral within the upper half of the bowl.

Below the stack of plates 6 and between the stack and the base 11 of the bowl is located a false bottom 14 provided on the back with a plurality of ribs or projections which converge towards the centre and form conduits 15 closed by two adjacent ribs, the base 11 of the bowl and the back of the false bottom 14.

The liquid distributed between the plates is subjected to their separating action, the clarified part of the liquid being the lighter is evacuated through the conduits 15 and reaches the outlet orifices 16 formed in the lower part of the bowl and surrounding and guiding the delivery tube 1. A small portion of the light liquid is also evacuated through the conduits formed by the superimposing of recesses 17 (Fig. 5) provided on the lower edge of the plates 6 and this portion is delivered to the orifices 16 through an aperture 18 in the false bottom 14.

At 19 is shown the receptacle for the clarified liquid.

On leaving the stack of plates 6, a part of the liquid surcharged with the heavy particles is forced by the centrifugal action towards the periphery of the bowl and towards the outlet orifices 20 for the sludge.

In accordance with the invention the arrangement is such that the liquid charged with heavy particles finds no support during its evacuation against which the solid particles could accumulate until the bowl becomes completely choked.

For that purpose the following arrangement has been devised which permits of evacuating the heavy particles in continuous process.

The lower part or base 11 of the bowl is of conical shape as is also the upper part 3 these two cones being joined at their bases. In this way the heavy particles can reach the periphery of the bowl which is the line of contact between the two cones.

As this separating line is circular the particles would however find a support thereon, even if this part of the bowl were provided with evacuation orifices.

In that case only the heavy particles would find their way during operation in front of these evacuation orifices which must of necessity be small (in the order of magnitude of some $\frac{1}{10}$ of a millimetre).

To eliminate this defect the lower part 11 of the bowl is so arranged that the spaces between the outlet orifices 20 are formed by angular portions 21 which with the upper cones 3 and the lower cone 11 of the bowl form funnels 22 the outlets of which coincide with grooves 20 of very short length provided tangentially in one of the faces of contact of the two halves of the bowl or in both these contact faces. These grooves afford the advantage as compared with holes of small dimensions, of being easy to make and easy to clean.

The angular portions 21 are joined together at 21¹ in such a manner as to form an arris taking part in the centring of the stack plates.

The two halves of the bowl are centred one on the other by a flange 23 (Fig. 3) provided on the upper part of the bowl and engaging around the upper peripheral rim of the lower part 11 of the said bowl. This flange 23 is recessed (as shown at 24, Fig. 3) opposite to the outlet orifices formed by the recesses 20 which reduces to a minimum the length of the evacuation grooves and permits

of minimising the resistance to the flow of the evacuated sludge.

The two halves of the bowl are joined together by bolts 25 which pass through the angular portions 21. These latter may be integral with the member 11 or the member 3 or they may consist of separate elements held in position by bolts 25 or again they may be cut on a horizontal plane such as for example at 29 and each of the parts would in that case be integral with the parts 3 and 11.

The grooves 20 and 24 are completely unobstructed owing to the absence of a joint consisting of a ring of rubber or analogous material generally provided between the upper half and the lower half of the known bowls. In the embodiment according to the invention, the only places which do not form a tight joint are those corresponding to the evacuation orifices.

20 The heavy substances accumulate in the casing 26 from which they are evacuated towards the outside at 21.

As will be readily understood the angular portions 21 also determine the angle of downward flow or slope of the heavy substances and it is possible to impart to the conical walls 3 or 11 an angle which is equal to or exceeds the said angle of flow. That is to say, the angular portions 21 have an inclination which corresponds to the angle of flow or slope of the heavy substances and the conical portions 3 and 11 are inclined so as to form an angle which is equal or which exceeds the angle of slope of the said substances.

For a given machine, it is only sufficient to modify the inclination of the conical portions 3 or 11 and that of the angular portions 21 (which can be interchangeable) in order to obtain a continuous evacuation with various materials having different angles of slopes. However the angle which will be chosen will be one suitable for the greatest series of materials.

Thanks to the construction described, the heavy particles separated from the liquid to be clarified can circulate freely in the bowl towards the evacuation orifices without encountering any obstacle.

In the construction described above the outlets for the muddy liquid consist of very short grooves provided tangentially in one of the contact surfaces of the two halves of the bowl or in both the said faces.

55 The utilisation of these grooves as a means of evacuation may not in practice yield advantageous results in view of the fact that these grooves may be expected to become worn by abrasion and in this way the quantity of muddy liquid evacuated will be increased by dilution.

With a view to maintaining the rate of flow through these orifices constant, the evacuation of the muddy liquid may be effected by means of 60 jewels (rubies, diamonds, etc.) pierced centrally with an accurately gauged hole and which are arranged in orifices provided in the bowl at the apex of the delivery funnels for the muddy liquid.

These jewels may be set directly in the bowl or 65 can be previously set in a circular ring (jewel-holder) which is inserted or screwed into the orifice drilled in the upper half or in the lower half of the bowl.

In addition, means may be provided whereby it 70 is possible to replace a jewel-holder set with a jewel of predetermined bore by another jewel-holder in which is set a stone having a different central hole.

In Fig. 6 is shown, as in the case of Fig. 1, the 75 tube 1 through which the liquid to be treated is

fed in, 2 the distribution chamber integral with the tube 1, 3 the upper half of the bowl, 6 the conical plates forming a stack and 11 the lower half of the bowl.

According to this modified embodiment of the invention, the outlet of the muddy liquid is effected through jewels 28 (ruby, diamonds, etc.) pierced centrally with a hole 29 of accurately gauged dimensions (Fig. 7).

In the example illustrated, these jewels are set in a jewel-holder 30 having the shape of a circular ring, for example of brass, stainless steel; etc., which is inserted into an orifice 31 drilled in the lower half 11 of the bowl opposite to the apex of the delivery funnels for the sludge. This lower half is provided with a flange 32 engaged around the lower peripheral rim of the upper part 3 of the bowl.

The jewel-holder 30 is held in position by a grub screw 33 having notches 34 used for tightening the screw (Fig. 7).

To place the jewel-holder in position, it is sufficient to insert it in the orifice 31 and fit the screw 33 in position which is tightened and locked, at the same time ensuring the locking of the jewel-holder 30.

It will be obvious that the jewel-holder may likewise be placed in an orifice provided in the upper part of the bowl opposite to the apex of the funnels delivering the sludge.

As the quantity of muddy liquid passing through the central orifice of the jewels is a function of the diameter of the said central orifice it is sufficient, in order to vary the quantity of muddy liquid expelled from the bowl; to vary the diameter of the bore in the jewels.

As the same are obtainable with different sizes of bore for one and the same external diameter, it will therefore be sufficient to replace the jewel-holder 30 fitted with a jewel of given bore by another jewel-holder in which is set a stone having a different central hole.

In other words if the bowl is fitted for example with jewels having a diameter of 0.3 mm. it is possible, in order to increase the quantity of muddy water to be expelled, to fit the same bowl with jewels having a central hole of 0.4, 0.5, 1 mm., 1.5 mm., etc.

The jewels may likewise be set directly in the bowl and in such case it is sufficient to drill the evacuation orifices provided in the bowl to the exact diameter of the stone and to set the latter permanently therein. This arrangement, however, precludes the possibility of varying the quantity of muddy liquid to be expelled which may, however, differ with the nature of the liquids to be clarified.

In consequence it is of interest to arrange matters in such a manner that the same bowl can be used for liquids of different natures or containing different quantities of sludge, by altering the bore of the jewels or by making the jewel-holders interchangeable with the aid of the means described above and illustrated in the drawings.

Irrespective of the arrangement adopted, the jewels retain in use a strictly constant diameter since any wear due to abrasion is practically impossible and the outlet of the evacuation orifices is thus maintained strictly constant.

Another modified embodiment of the bowl shown in the drawings consists in the fact that

the assembling bolts 35 for the top 3 and of the bowl (Fig. 6) and the bottom half 11 are housed into these main parts whereas in the embodiment previously described these bolts emerge at the top of the bowl. This improvement permits of reducing the power absorbed by the bowl in motion.

What I claim is:

1. A centrifugal separating bowl for continuous separation of liquids comprising a casing formed of upper and lower halves of conical shape and being joined along their meeting edges, a feed conduit disposed centrally within said bowl and having a flared extension forming a distribution chamber supported in the upper portion of said bowl, vanes vertically arranged and radially disposed in said distribution chamber to impart rotary motion to the liquid received therein, a pack of frusto-conical discs disposed in said bowl below said distribution chamber and around said feed conduit, said discs being spaced in superposed relationship to one another, ports arranged in said flared extension between said vanes, leading to said discs, each disc of the pack having openings formed therein which constitute substantially vertical conduits when said openings are vertically aligned, said conduits being in communication with said ports and with a discharge opening at the lower end of said bowl; jet discharge openings for heavy bodied material arranged in the periphery of the meeting edges of said casing, angular members having material depositing surfaces arranged within the casing around said discs and adjacent the said discharge openings, the vertical walls of said members cooperating with the casing walls to form funnels converging towards said jet openings, the inwardly extending arris of each of said angular members contacting the outer peripheral edges of said discs, and means passing through said casing halves and said angular members to secure them in assembled relation, said angular members being fixed and immovable with respect to said jet openings.
2. A device according to claim 1 in which the lower half of the casing slopes uninterruptedly towards a discharge opening surrounding the feed conduit, the angular members being supported and secured on said sloping surface, the securing means comprising bolts.

FERNAND JEAN JOSEPH JULIEN
HENRARD.
